UNITED STATES PATENT OFFICE.

ALFRED C. NELSON, OF LAKEWOOD, AND EDGAR J. REILLY, OF YOUNGSTOWN, OHIO,
ASSIGNORS TO THE WILLIAM B. POLLOCK COMPANY, OF YOUNGSTOWN, OHIO, A
CORPORATION OF OHIO.

LIQUID-METAL TRANSFER APPARATUS.

Application filed February 16, 1922. Serial No. 526,902.

To all whom it may concern:

Be it known that we, ALFRED C. NELSON and EDGAR J. REILLY, citizens of the United States, residing at Lakewood, county of 5 Cuyahoga, Ohio, and Youngstown, county of Mahoning, State of Ohio, respectively, have invented a new and useful Improvement 10 in Liquid-Metal Transfer Apparatus, of which the following is a full, clear, and exact description, reference being had to the accompanying drawings, forming part of this specification, in which—

Figure 1 is a top plan view of an apparatus constructed in accordance with the 15 present invention, and

Figure 2 is an end elevation of the construction illustrated in Figure 1.

The present invention relates broadly to apparatus for the transfer of liquid metal, 20 and more particularly to an apparatus whereby metal as delivered in molten condition from a furnace may be transferred to molds or the like.

It has heretofore been proposed to construct 25 ladles adapted to be normally supported in fixed bearings which are either in the form of stands definitely located, or carried by cars. Most of these devices have been constructed for use with open top ladles. The present invention has relation more 30 particularly to an apparatus adapted to utilize a cylindrical or closed ladle and embodies improvements in the mounting thereof whereby the ladle may be moved from one position to another with a minimum 35 expenditure of power.

Referring more particularly to the drawings, there is disclosed an apparatus of the character referred to comprising a delivery 40 spout 2 adapted to receive molten metal from a furnace, not shown, at one end and deliver the same to a ladle or ladles 3. This spout is provided with a pivotal mounting 45 5 whereby it may be moved to inoperative position as shown in Figure 2 by dotted lines, when it is desired to empty the ladle 3. For effecting such movement of the spout 2 there may be provided an operating cable 5 secured in any desired manner 50 to the free end of the delivery spout and thence passing over a pulley 6 carried by the crane frame 7.

With the parts in the position illustrated in full lines in Figure 2 metal delivered to

the spout 2 will be discharged into the ladles 55 3 through the openings 8. Each of these ladles is preferably of the closed or cylindrical type having secured to each end thereof an eccentrically mounted trunnion 9. These trunnions are carried by open top 60 bearings 10 mounted on a frame work 11 supported adjacent the pit 12 in any desired manner. At one side of the trunnions 9 are formed stops 13 adapted to definitely position the ladles when receiving molten 65 metal

For discharging the ladles, they may be provided with yokes 14 for the attachment of a flexible cable 15 the opposite end of which is secured to an eyelet 16 adapted to 70 receive the hoisting hook 17 of an overhead crane 18 of any desired construction. By reason of the construction provided it will be apparent that the initial lifting movement of the hook 17 is effective for producing a true rotational movement of the ladles about the axis of rotation A of the trunnions 9 within the bearings 10. This rotational movement will have the effect of gradually shifting the center of gravity B 75 80 of the liquid content of the container from the position shown in full lines in Figure 2. This operation will continue until the open bearings 19 projecting upwardly from the ladles engage the stationary pins 20 85 mounted in the stands 21. Continued upward movement of the hooks 17 will result in lifting the ladles bodily from the bearings 10 and produce a rotational movement thereof about the pins 20. This movement 90 95 will be effective for bringing the discharge spouts 22 into cooperative relation with the runner 23. This runner may deliver the molten metal to molds 24 or other devices as may be desired.

While we have illustrated a plurality of ladles, it will be apparent that a single ladle may be utilized if desired, and that the delivery spout and runner may be correspondingly modified.

By reason of the construction provided, we are enabled to obtain the advantages resulting from the use of closed ladles. The ladles may also be operated with a minimum of power about their eccentric trunnions by 105 reason of the initial rotational movement which is effective for shifting the center of gravity of the molten material and also for

shortening the effective distance between the pin 20 and the center of gravity of the material before the ladle is bodily lifted. These constitute important advantages of the present invention.

It will be understood that the ladles 3 may be mounted on movable carriers if desired and that other changes may be made in the construction and operation of the 10 ladles without departing from the spirit of our invention or scope of our broader claims.

We claim:

1. In an apparatus of the character described, a rotatable ladle of the closed type, 15 eccentrically mounted trunnions on the ends thereof, open top bearings adapted to cooperate with said trunnions, and means for producing an initial rotational movement about said trunnions to shift the center of 20 gravity of the material within the ladle and to thereafter elevate the ladle and discharge its contents, substantially as described.

2. In an apparatus of the character described, a rotatable ladle of the closed type, 25 eccentrically mounted trunnion on each end of said ladle, a stop cooperating with said trunnions to normally hold the ladle in position to receive molten metal, a stand, a bearing carried by said ladle and adapted 30 to cooperate with said stand, and means for initially rotating said ladle about said trunnions and thereafter moving said bearing into engagement with said stand to discharge

the contents thereof, substantially as described.

3. In an apparatus of the character described, a rotatable ladle of the closed type, an eccentrically mounted trunnion on each end of said ladle, a stop cooperating with said trunnions to normally hold the ladle in 40 position to receive molten metal, a stand, a bearing carried by said ladle and adapted to cooperate with said stand, means for initially rotating said ladle about said trunnions and thereafter moving said bearing 45 into engagement with said stand to discharge the contents thereof, and a pivotally mounted delivery spout cooperating with said ladle, substantially as described.

4. In an apparatus of the character described, a rotatable ladle of the closed type, eccentrically mounted trunnions on the ends thereof, open top bearings adapted to cooperate with said trunnions, means for producing an initial rotational movement about 50 said trunnions to shift the center of gravity of the material within the ladle and to thereafter elevate the ladle and discharge its contents, and a pivotally mounted delivery 55 spout cooperating with said ladle, substantially as described.

In testimony whereof we have hereunto set our hands.

ALFRED C. NELSON.
EDGAR J. REILLY.
